CLAIM

I claim, the ornamental design for a computer, as shown and described.

DESCRIPTION

FIG. 1 is a perspective view of a computer, showing my new design;

FIG. 2 is a top down plan view of the design of FIG. 1;
 FIG. 3 is a bottom up plan view of the design of FIG. 1;
 FIG. 4 is a front elevation view of the design of FIG. 1;
 FIG. 5 is a rear elevation view of the design of FIG. 1;
 FIG. 6 is a left side elevation of the design of FIG. 1; and,
 FIG. 7 is a right side elevation view of the design of FIG. 1.
 The broken lines shown in the drawings illustrate portions of the computer that forms no part of the claimed design.
